GAME APPARATUS

John F. Meyer, Chicago, Ill.

Application November 24, 1933, Serial No. 699,492

7 Claims. (Cl. 273—142)

This invention relates to game apparatuses.

It is an object of this invention to provide a novel amusement game apparatus that is relatively simple and inexpensive in construction and entertaining in use.

Another object of the invention is to provide a novel amusement game apparatus comprising the combination of (1) a rotatable horizontal table or disc, that is, a spinning disc on which

10 a variety of objects such, for example, as colored balls or the like, may be arranged to be tumbled around upon the disc by the spinning movements of the same so as to afford amusement to the player watching their changing positions, 15 movements, or sequences; (2) a coin slide; and (3) means operatively associated with the coin slide and disc for spinning the disc by movement of the coin slide, that is, means for transforming slidable movement of the coin slide into spinning or rotatable movement of the disc.

Another object of the invention is to provide novel means for preventing fraudulent operation of the apparatus.

Related to the last-named object but more specific, a further object of the invention is to provide a novel means for preventing the spinning operation of the disc until the coin slide has returned to ineffective or idle position.

Other objects will appear hereinafter.

30 The invention consists in the novel combination and arrangement of parts to be hereinafter described and claimed.

The invention will be best understood by reference to the accompanying drawings, showing the preferred form of construction and in which:

35 Fig. 1 is a top plan view of the new game apparatus, with a part of the casing or cabinet thereof removed, and showing the coin slide and operating mechanism associated therewith in idle or initial position;

40 Fig. 2 is a top plan view similar to Fig. 1 but showing the coin slide and operating mechanism associated therewith in the position they assume just prior to the disc-spinning operation;

45 Fig. 3 is a longitudinal, vertical sectional view on line 3—3 in Fig. 6;

Fig. 4 is a transverse sectional view on line 4—4 in Fig. 6;

50 Fig. 5 is a fragmentary sectional detail view on line 5—5 in Fig. 6; and

Fig. 6 is a top plan view of the new game apparatus.

The drawings show a preferred form of the new game apparatus and therein a cabinet is generally indicated at 10 and has a transparent

top wall 11 below which and within or upon the cabinet 10 the operating parts of the new game apparatus are arranged.

Associated with one of the vertical walls 12 of the cabinet 10 is a coin control device generally indicated at 13, and including a coin slide 14 having a coin slide return spring 43 associated therewith. While this coin control device 13 may be of any approved type, it is preferably the efficient coin slide described in the following patents: No. 1,908,380 issued to Walter A. Tratsch, May 9, 1933 and No. 1,908,752 issued to Louis M. Hall, May 16, 1933, since the slide described in these patents has found wide acceptance in the amusement game trade.

5 Mounted upon a suitable supporting base 15 in the cabinet 10 is a base plate 16 upon which, in turn, is mounted a vertical bearing stud 17 (Fig. 4). Anti-frictionally mounted for rotatable movement on the bearing stud 17 is a gear or pinion 18 which carries a spinning table or disc 19 that is fast upon the gear or pinion 18 at the top of the latter, and so as to spin within the cabinet 10 under the transparent top 11 thereof.

20 In one form of the new apparatus scoring indicia may be arranged upon the upper surface of the spinning disc 19, such, for example, as a clock-like row of numerals (not shown) movable relative to and into registry with a fixed 30 preselected scoring or indicating point 21 on the transparent top wall 11; or the top surface of the disc 19 may be divided into variously colored segments, and the scoring value of each play may be determined by registry of a preselected 35 colored segment of the disc 19 with the fixed preselected scoring point or indicator 21 when the disc 19 comes to rest after each spinning operation.

Operatively associated with the coin slide 14 40 and with the gear or pinion 18 so as to rotate or spin the disc 19 each time a coin of the proper denomination is inserted into the coin slide 14, and the coin slide 14 is operated are means now to be described.

To this end there is provided on the inner end of the coin slide 14 a lateral projection 22 having an angularly extending cam face 23 which bears against a vertical projection 24 of a horizontal arc-shaped bar 25 that is pivotally mounted, adjacent one end, upon the base plate 16, as at 26. The vertical projection 24 of the bar 25 is urged against the cam face 23 of the coin slide projection 22 by means of a spring 27 which has one end fixed to the base plate 55

16 and which has its other end attached to the bar 25 (Figs. 1 and 2).

Having one end pivotally mounted upon the base plate 16, as at 28, is a horizontal bar 29. 5 This bar 29 has a depending or downwardly extending projection 30 at its other end and this projection 30 is adapted, in a manner presently to be described, to ride the inner and arcuate face 31 of the bar 25.

10 Pivotedly connected at one end, by means of a pin 32, to the bar 29, adjacent the downward projection 30 of the latter, is a horizontal rack bar 33, the teeth of which are adapted to engage with the teeth of the pinion or gear 18 to 15 rotate or spin the pinion 18 and the disc 19.

15 The free end portion of the rack bar 33, that is the end portion thereof that is opposite the end that is pivotally connected at 32 to the bar 29, is guided for movement by means of a 20 lug or pin 34 which is carried by the rack bar 33 and works in a groove 35 formed in the base plate 16. This pin 34 is urged downwardly, relative to the rack bar 33 and against the bottom of the groove 35 by means of a flat leaf spring 37 which is carried by the rack bar 33. 25

25 The groove 35 opens at its outer end out onto the upper surface of the base plate 16 by way of an inclined groove or outlet 36 (Fig. 1) which is continuous with the groove 35.

30 Having one end attached to that end of the rack bar 33 that is opposite the end having the pivotal connection at 32 with the bar 29 is a coil spring 38 which has its other end suitably fixed to the cabinet 10.

35 Projecting upwardly from the rack bar 33 is a stop lug 39 and adapted to engage the stop lug 39 at a certain time in the cycle of operations presently to be described is a stop bar 40 which is mounted on the base plate 16 and has a portion projecting over the rack bar 33.

40 Formed in the bar 25 is a latching notch or 45 detent 41, the purpose of which will be made apparent presently.

Operation

45 The spring 27 urges the bar 25 (counter-clockwise Fig. 1), causing the upwardly projecting portion 24 of the bar 25 to bear against the angled cam face 23 of the lateral projection 22 of the coin slide 14. However, when a coin 50 of the proper denomination is inserted into the coin slide 14 and the coin slide 14 is pushed inwardly toward coin releasing or operative position, the projection 24 of the bar 25 rides off the angled cam face 23 of the coin slide projection 22 whereupon the spring 27 urges the bar 25 55 (counter-clockwise, Fig. 1), thus causing the inner and arcuate face 31 of the bar 25 to engage the downwardly extending projection 30 of the bar 29.

60 Further inward movement of the coin slide 14 and its lateral projection 22 causes the latter to engage (Fig. 2) the pin 32 which provides the pivot connection between the bar 29 and the rack bar 33, a portion of this pin projecting above (Fig. 3) the upper surface of the bar 29.

65 Continued inward movement of the coin slide 14 and its lateral projection 22 (now in engagement with the pivot pin 32) pivots the bar 29 (clockwise Figs. 1 and 2). This movement of the bar 29 moves the rack bar 33 and associated parts from their positions of Fig. 1 into their 70 positions of Fig. 2, during which movement the pin 34 rides through the groove 35 and up out of the groove 35, by way of the inclined groove

36, onto the upper surface of the base plate 16. This movement of the parts of the operating mechanism causes the teeth of the rack bar 33 to mesh with the pinion 18, tensions the coin slide return spring 43 and the spring 38, and 5 positions one corner portion 42 of the bar 29 in engagement with the latching notch or detent 41 formed in the bar 25 (Fig. 2). This is the position of the parts (as shown in Fig. 2) at the time the coin slide reaches its innermost position, at which time the slide has released the coin carried thereby into the cabinet 10 and is ready to start its return movement which is accomplished by the tensioned spring 43.

10 During the time the coin slide 14 is being returned to idle position by the tensioned spring 43, the corner portion 42 of the bar 29 is held by the action of the spring 27, in latching engagement with the latch notch or detent 41 formed in the bar 25. This latching engagement of the corner portion 42 of the bar 29 in the notch 41 prevents movement of the bar 29, and also prevents movement of the rack bar 33 and the pinion 18 and the disc 19 carried by the pinion 18. This latching engagement is 15 maintained and movement of the bar 29, rack bar 33, pinion 18 and disc 19 prevented until the angled cam face 23 of the lateral coin slide projection 22 engages the upwardly extending projection 24 of the bar 25 which occurs at the 20 time the coin slide 14 completes its return to idle or ineffective and locked position (Fig. 1). However, as the cam face 23 of the lateral coin slide projection 22 engages the upwardly extending projection 24 of the bar 25, the bar 25 25 is pivoted (clockwise from full to dotted line position, Fig. 2), thereby releasing the corner portion 42 of the bar 29 from latching engagement in the notch 41 formed in the bar 25, whereupon the tensioned spring 38 pulls the 30 rack bar 33 (the teeth of which are at this time in mesh with the pinion 18) rapidly across the face of the pinion 18 from the position of Fig. 2 into the position of Fig. 1, thereby rapidly spinning the gear or pinion 18 and the disc 19 carried thereby (clockwise, Figs. 1 and 2). At the 35 end of this movement the rack bar 33 is positioned (as in Fig. 1) out of mesh with the pinion 18 so that the pinion 18 and the disc 19 are free to continue the rotation imparted thereto by the aforementioned rapid movement of the rack bar 33.

40 During this movement of the rack bar 33 the pin 34 rides across the upper surface of the base plate 16 and is returned into the groove 35 by the action of the flat spring 37, the bar 40 preventing the spring 38 from lifting the rack bar 33 up out of its path of movement. At the 45 time the rack bar 33 reaches its initial position it is stopped by engagement of the pin 39 with the stop bar 40.

50 The aforementioned delayed release of the corner portion 42 of the bar 29 from latching engagement in the notch 41, which does not take place, as hereinbefore stated, until the cam face 23 of the lateral coin slide projection 22 engages the arcuate face 31 of the bar 25, prevents 55 fraudulent operation of the game apparatus by manipulation of the coin slide 14 since this delayed release takes place practically simultaneously with the movement of the coin slide 14 into locked, idle position; in which position the coin slide 14 is held (by means not shown) until a coin of the proper denomination is in- 60

serted into the coin receiving opening formed therein.

Another device is provided for preventing fraudulent operation of the apparatus by manipulation of the coin slide 14 and this device comprises a spring-urged latch dog 44 that is pivotally mounted on the coin control device 13 adjacent one longitudinal edge of the coin slide 14. This dog 44 engages in a serrated edge 45 of the coin slide 14 to prevent fraudulent return or retroactive movement of the coin slide 14 until the latter has reached its innermost position. This device 43-44 also prevents fraudulent forward movement of the coin slide 14 once the latter has reached the inner end of its travel and started back to idle position in which it is shown in Fig. 1.

Formed in the same edge of the coin slide 14 that has the notches 45 formed therein (Fig. 2) is a notch 48. As the coin slide 14 is moved inwardly the dog 44 is spring-urged (by a spring not shown) into the notch 48 so that the dog 44 faces inwardly and engages the notches 45. This prevents rearward movement of the coin slide 14 until the notched edge portion 45 of the slide 14 has passed the dog 44. On the return movement of the slide 14 the dog 44 is again spring-urged into the notch 48 which pivots the dog (clockwise, Fig. 2) thereby pointing the dog 44 rearwardly so that the dog engages the notched edge 45 in such a manner that it prevents inward movement of the slide 14 until the notched edge 45 has passed the dog 44.

The apparatus includes a board 46 which extends (Fig. 3) transversely across the cabinet 10 between the transparent top wall 11 and the disc 19, and has an annular opening or pocket 47 extending vertically therethrough. This opening 47 provides a pocket or receptacle which is made coincident with, that is, of the same size as, the disc 19, so that variously colored amusement balls or the like (not shown) may be arranged in the pocket or receptacle 47 upon the disc 19. When the disc 19 is rapidly spun the balls or like objects in the pocket 47 will be tumbled around upon the upper surface of the disc 19, below the transparent top wall 11, to afford amusement to the player watching the changing positions and tumbling movements of the balls or the like.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A game apparatus, comprising the combination of: a cabinet having a substantially horizontal transparent top; a rotatable gear member arranged in the cabinet; a disc carried by said gear member, so as to be rotatable therewith, between said gear member and said transparent top; a coin control device arranged at a point on the cabinet and including a coin slide; means

operatively interconnecting said coin slide and said gear member for converting sliding movement of said coin slide into rotating, spinning movement of said gear member and disc; a latching mechanism associated with said means and coin slide; said latching mechanism being rendered effective by movement of said coin slide into coin-releasing position and being released by the return movement of said coin slide into idle position so as to delay rotation of said gear member and disc until the coin slide has completed its movement into coin-releasing position and is returning to idle position; and means cooperating with said disc to provide a pocket in said cabinet between the said top thereof and said disc for the reception of a ball or the like.

2. In a game apparatus, the combination of: a cabinet; a disc rotatably mounted in said cabinet; a coin slide mounted in a wall of said cabinet; means coacting with said coin slide for rotating said disc; and means including a device released by movement of said coin slide from coin-discharging position into coin-receiving position for latching said disc against rotation.

3. In a game apparatus, the combination of: a cabinet; a disc rotatably mounted in said cabinet; a coin slide mounted in a wall of said cabinet; means, including a device energized by movement of said coin slide from coin-receiving position into coin-discharging position, for rotating said disc; and means including a device released by movement of said coin slide from coin-discharging position to coin-receiving position for latching said disc against rotation.

4. In a game apparatus, the combination of: a cabinet; a disc rotatably mounted in said cabinet; a coin controlled member mounted in a wall of said cabinet; means coacting with said coin-controlled member for rotating said disc; and means for delaying the rotation of said disc until said coin controlled member has completed substantially a full stroke.

5. In a game apparatus, the combination of: a cabinet; a disc rotatably mounted in said cabinet; a coin slide mounted in a wall of said cabinet; means coacting with said coin slide for rotating said disc; and means for delaying the rotation of said disc until said coin slide has completed substantially a full stroke.

6. In a game apparatus, the combination of: a cabinet; a disc rotatably mounted in said cabinet; a coin controlled member mounted in a wall of said cabinet; means coacting with said coin controlled member for rotating said disc; and means, including a device released by movement of said coin controlled member, for delaying the rotation of said disc until said coin controlled member has completed substantially a full stroke.

7. In a game apparatus, the combination of: a cabinet; a disc rotatably mounted in said cabinet; a coin slide mounted in a wall of said cabinet; means coacting with said coin slide for rotating said disc; and means, including a device released by movement of said coin slide, for delaying the rotation of said disc until said coin slide has completed substantially a full stroke.
